C. DAHL

MONOPLANE KITE

Filed Sept. 20, 1923

UNITED STATES PATENT OFFICE.

CONRAD DAHL, OF CHICAGO, ILLINOIS, ASSIGNOR TO ROBERT N. BURTON, OF CHICAGO, ILLINOIS.

MONOPLANE KITE.

Application filed September 20, 1923. Serial No. 663,750.

To all whom it may concern:

Be it known that I, CONRAD DAHL, a citizen of the United States, residing at Chicago, in the county of Cook and State of Illinois, have invented certain new and useful Improvements in Monoplane Kites, of which the following is a specification, reference being had to the accompanying drawings forming a part thereof.

This invention represents an improvement and refinement of the kite design shown and described in my application for Letters Patent, Serial No. 636,823, filed May 5, 1923, and it has for its object the further simplification of the device for manufacture and the improvement of its steadiness and efficiency in use.

It consists of certain features and elements of the construction herein described and shown in the drawings, as particularly indicated by the claims.

In the drawings:

Figure 1 is a bottom plan view of the kite embodying this invention.

Figure 2 is a front elevation of the same.

Figure 3 is a side elevation showing the kite approximately in the position of flight.

Figure 4 is a perspective view of the kite as seen from above.

Figure 5 is a detail view illustrating a feature of construction.

Figure 6 is a fragmentary side elevation showing the attachment of the rudder plane to a vertical strut and the mid rib.

The framing for this kite consists of a longitudinal mid rib, 1, to which a cross arm, 2, is attached near its forward end, while a cross arm, 3, similar in length to the arm, 2, is supported at a distance above the mid rib, 1, by securement to a vertical strut, 4, rising from the mid rib and partially held in this position by lateral guys, 5, extending from its upper end to the outer ends of the cross arm 3. Guys, 6, extend

from the forward end of the mid rib, 1, to points on the cross arm, 2, at opposite sides of its mid point, and guys, 7, similarly connect the cross arm, 3, with the rear end of the mid rib, 1. By means of these guys, 6

and 7, a main sail, 8, is held in stretched condition between the cross arms, 2 and 3, being attached to the forward cross arm, 2, substantially throughout its width by a hem or like tubular connection at 9, while its

rear edge is connected to the arm, 3, at op-

posite ends of the latter by short strings engaging eyelets, 10, in the corners of the sail, 8. Inwardly from these points similar strings engage eyelets, 11, in the rear edge of the sail for anchoring to the cross arm, 3, with the material unattached between the eyelets, 10 and 11, to permit a slight swelling of the sail under wind pressure, allowing the wind to escape at the rear edge between these points of anchorage instead of forming a pocket in the sail.

Still nearer to the mid rib, 1, than the eyelets, 11, the sail is provided with eyelets, 12, through which a continuous cord, 13, passes freely with its ends secured at 14, 14, to the cross arm, 3. The portion of the sail between the eyelets 12, 12, extends downwardly around the under side of the mid rib at 16, thus forming itself into upwardly diverging plane portions 17, 17, which tend to deflect the wind equally to the two broad areas of the sail, which are stretched in the common plane of the cross arms, 2 and 3. The middle portion of the sail is left unattached to the mid rib at 16, so that in view of the free sliding engagement of the cord, 13, with eyelets, 12, the sail can adjust itself so as to equalize the tension at the several points of attachment, and its two main areas at opposite sides of the mid rib will present substantially similar surfaces to the wind.

A triangular jib sail, 18, is attached to the main sail, 8, at 18^a with its apex extending forwardly for securement to the forward end of the mid rib, 1. The sail, 18, thus lies in the common plane of the cross arm, 2, and the mid rib, 1, and thus stands at an angle to the principal plane of the sail, 8, forming a small banking plane 95 against which the pressure of the wind will tend at all times to hold the forward end of the kite tilted upwardly as shown in Figure 3.

The cross arm, 3, is attached to the strut, 4, preferably by readily disengageable means. As shown in Figure 6, the strut is notched at 20 to receive the cross arm which is bound in position by a string 21, wrapped about both members. If desired, a second 105 notch, 22, may be provided at a lower point in the strut, 4, so that for certain conditions the cross arm, 3, may be mounted in this lower position to alter the angle of the main sail, 8. This adjustment may be made 110

when it is desired to fly the kite in a particularly heavy wind.

The remainder of the construction is also devised to permit the parts to be quickly 6 disassembled for convenience in transporting the kite from place to place. The upper end of the strut, 4, is formed with a notch, 23, having a middle enlargement, 23^a, formed by drilling a hole into the end of 10 the strut; the guy string, 5, has a knot, 5^a, tied at its mid point, so that when the string is lodged in the notch, 23, the knot will enter the enlargement, 23^a, and thus anchor the string in the strut. A similar construction may be applied to the ends of the 15 mid rib at 24 and 25 for accurate engagement of the guy strings, 6 and 7.

For steadyng the kite and giving it a 20 definite direction of flight, the rudder plane, 30, extends vertically upward from the mid rib, 1, and longitudinally thereon from the strut, 4, rearwardly almost to the end of the mid rib. From the upper edge of the rudder plane, 30, at the rear half thereof, 25 the banking planes, 31, extend laterally for engagement of their edges with the guys, 7. For manufacturing convenience the plane 31 and the rudder plane 30 may be made of a single piece of cloth or paper folded 30 about the mid rib, 1, to form a sleeve, 32, engaging it, thus making the rudder portion, 30, of double thickness with the banking wings, 31, each of single thickness, folded out from its upper edge. For stiffening the rudder plane a reenforcing strip, 33, 35 of wood may be attached exteriorly as shown, or may be glued in position between the two plies of the plane, 30. The upper and forward corner of said plane is anchored to the cross arm, 3, by a string, 34, engaging an eyelet, 35, in the plane, 30. Similarly an eyelet, 36, at the rear corner of the plane receives a string, 37, extending 40 to the end of the mid rib, 1.

45 For holding the kite in flight, I provide a pair of strings, 40, 40, extending from the cross arm, 2, substantially at the points at which guys 6, 6, are connected; a third string, 41, extends from the extreme rear end of 50 the mid rib, 1, and these three strings are tied to a short equalizer bar, 42, the string, 41, to its mid point, and the strings, 40, to its opposite ends. The main leading string, 43, is attached to the mid point of the bar, 42, as shown in Figures 2 and 3.

I claim:

1. In a kite, the combination of a longitudinal mid-rib, a cross arm secured thereto near the forward end, a second cross arm 60 positioned rearwardly of the first and spaced above the common plane of said first cross arm and the mid-rib, a main sail stretched between said cross arms with most of its area disposed in their common plane 65 but having its middle portion drawn down-

wardly to the mid-rib forming a pair of upwardly flaring surfaces to deflect the wind to both lateral areas of the main sail.

2. In the combination defined in claim 1, 70 said main sail being attached to the first cross arm substantially throughout its width and being attached to the second cross arm at its corners and at two other points equidistant from the mid-rib.

3. In the combination defined in claim 1, 75 said middle portion of the main sail being unattached to the mid-rib and being laterally defined by a pair of eyelets in the sail at its rear edge and at opposite sides of the mid-rib with a cord passing freely through 80 said eyelets above the mid-rib and having its ends anchored to the second cross arm.

4. In the combination defined in claim 1, 85 a triangular jib sail or banking plane extending forwardly from the main sail at the first cross arm with its apex attached to the forward end of the mid-rib whereby said jib sail extends forwardly and upwardly at an angle with respect to the principal 90 plane of the main sail.

5. In the combination defined in claim 1, 95 a triangular jib sail or banking plane inclined upwardly from the main sail at the first cross arm with its apex attached to the forward end of the mid-rib and a pair of banking planes supported rearwardly of the main sail at opposite sides of the vertical plane of the mid-rib and also inclined upwardly with respect to the principal plane 100 of said main sail.

6. In the combination defined in claim 1, 105 said mid-rib extending rearwardly of the second cross arm, guys connecting the rear end of said mid-rib with laterally separated points on the cross arm, a rudder plane 110 standing from the mid-rib substantially to the height of the second cross arm above the mid-rib and tapering down toward the rear with banking planes extending from both sides of said rudder to the guys.

7. In a kite, the combination of a longitudinal mid-rib, a cross arm secured thereto near the forward end, a second cross arm positioned rearwardly of the first and spaced above the common plane of said first cross arm and the mid-rib, a main sail 115 stretched between said cross arms at an angle to said common plane, said mid-rib extending rearwardly of the second cross arm, banking sails disposed above the rearwardly extending portion of the mid-rib at both sides of its vertical plane and inclined downwardly from the plane of the main sail and a leading string extending from the middle of an equalizer bar with a pair of 120 strings connecting the ends of said bar with the first cross arm at opposite sides of its middle and a third string extending rearwardly to the rear end of the mid-rib.

8. In a kite, the combination of a longi- 125

tudinal mid-rib, a cross arm secured thereto near the forward end, a second cross arm positioned rearwardly of the first and spaced above the common plane of said first cross
5 arm and the mid-rib, a main sail stretched between said arms, a rudder plane upstanding from the mid-rib and banking planes disposed fore-and-aft of the main sail respectively inclined forwardly and upwardly
10 and rearwardly and downwardly with respect thereto.

9. In a kite, the combination of a longitudinal mid-rib, a cross arm secured thereto near the forward end, a second cross arm
15 positioned rearwardly of the first and sup-

ported above it by a vertically extending strut, said strut having a notch to accommodate the cross arm and a second notch at a different distance from the mid-rib and means for retaining said cross arm in either 20 notch together with a main sail adapted to be stretched between said first and second cross arms and banking planes mounted fore-and-aft of the main sail respectively in fixed angular relation to the common plane 25 of the mid-rib and the first cross arm.

In testimony whereof, I have hereunto set my hand at Chicago, Illinois, this 18th day of September, 1923.

CONRAD DAHL.
